(57) CLAIM

We claim the ornamental design for a toothbrush handle, as shown and described.

DESCRIPTION

FIG. 1 is a front elevational view of a toothbrush handle showing our new design; and,

FIG. 2 is a bottom, front, left side perspective view of the toothbrush handle of FIG. 1.

The broken lines showing the rest of the handle and a brush head are included for the purpose of illustrating portions and environmental structure of the toothbrush handle that form no part of the claimed design.
